CATCH BASKET FOR CLOTHES CHUTES

Carl E. Carlson, Minneapolis, Minn., assignor to
Leslie R. Carlson, Minneapolis, Minn.

Application November 19, 1938, Serial No. 241,443

1 Claim. (Cl. 232—1.2)

My invention provides an improved catch basket for clothes chutes. The term "basket" is herein used as a broad term to include receptacles which might also be designated as boxes, racks, or the like. However, the basket should be made with open or aerated sides and bottom so that damp clothes dropped therein from the clothes chute will have a chance to dry by the circulation of air therethrough.

The invention consists chiefly in the novel manner of hanging the basket so that when it is dropped from a receiving position to an open or discharging position, it can be lowered from the ceiling so that the clothes will not be discharged therefrom and may easily be reached by a person standing on the floor of a basement or room where the device will usually be installed.

A preferred embodiment of the invention is illustrated in the accompanying drawings where-in like characters indicate like parts throughout the several views.

Referring to the drawings:

Fig. 1 is a view in perspective with some parts sectioned showing the catch basket in position to receive the clothes from the delivery end of the clothes chute, the dropped position of the basket being indicated in part by dotted lines;

Fig. 2 is a fragmentary section taken on the line 2—2 of Fig. 1;

Fig. 3 is a fragmentary section taken on the line 3—3 of Fig. 1;

Fig. 4 is a fragmentary section taken on the line 4—4 of Fig. 1;

Fig. 5 shows the ceiling floor in section, the basket in normal position by dotted lines, and the basket in a dropped position by full lines; and

Fig. 6 is a detail in section with parts broken away showing the modified form of latch link for holding the basket in working position.

Referring first to the preferred arrangement shown in Figs. 1 to 5 inclusive, the numeral 10 indicates the floor of a dwelling or the ceiling of a basement, which flooring structure includes the customary floor joists 10'. Numeral 11 indicates the clothes chute extended through the flooring 10.

The basket is preferably constructed of wooden slats 12 and corner posts 13, nailed or otherwise secured together in rectangular form to form an open or ventilated basket. This basket will be located immediately below the clothes chute 11. At one end the basket is supported by hanger links 14, and at the opposite end by a latch link 15,

which latter is preferably a wire V-shaped structure.

The links 14, at their upper ends, are bent to form hooks that are preferably hung in eyelets 16, or the like, applied to the overlying floor joists 10' at the rear of the basket; and at their lower ends said links 14 are bent to form hooks that are pivoted in eyelets 17 applied to the lower portion of the adjacent side or end of the basket.

The latch link 15, as stated, is preferably V-shaped or divergent, and is bent at the upper ends of its prongs to form hooks that are pivoted through eyelets 16 applied to the floor joists 10' at the front end of the basket. At their lower ends the prongs of the link 15 are twisted together or otherwise joined, and are bent laterally to form a loop 19, and beyond the loop a projecting finger 20.

To lock the basket in working position, the lower end of the latch link is engaged with the bottom part of the adjacent end of the basket, with the bottom slat of the basket seated in the loop 19, as shown by full lines in Fig. 1, and by dotted lines in Fig. 5.

With the device positioned as shown by full lines in Fig. 1, the basket is, of course, in position to receive the clothes from the clothes chute.

When the latch link 15 is swung to the left in respect to Fig. 1, the basket will drop into the position indicated by dotted lines in Fig. 1 and by full lines in Fig. 5. As the basket is thus dropped, it lowers its position so that the contents will be within easy reach of a person standing on the basement floor. If the clothes do not drop out, they may be easily removed while the basket is in the position shown in Fig. 5; and if it is desired to dump the complete load, the basket may be turned completely upside down by swinging it on the pivot eyelet 17 toward the right in respect to Fig. 5. Also, the links 14 permit the basket, when turned upside down, to be moved bodily either toward the left or toward the right so that the clothes will be dumped just where desired or in any underlying receptacle if such be employed. Obviously the basket may be easily returned to normal position and there again latched in position to receive clothes from the chute. The braced or V-shaped link 15, when applied as shown in Fig. 1, also steadies and holds the basket against forward or rearward movements; that is, movements in a position parallel to the plane of the said link.

Fig. 6 illustrates a modified form of latch wherein, as a substitute for the link 15, there is provided a hanger link 21 that is pivoted to the

ceiling floor 10 by means of a hanger bracket 22. This link extends down to a position below the bottom of the basket so that it may be readily manipulated. The basket at its swinging end 5 and near its top is provided with a latch lug 23 that is adapted to be engaged by a latch lug 24 on the intermediate portion of the link 21.

From the foregoing it will be understood that the device described and illustrated in the drawings is capable of modifications within the scope 10 of the invention herein disclosed and claimed.

What I claim is:

The combination with an overhead support and a delivery chute therein, of a basket normally located below said chute, individual links independently and freely pivoted to said support at their upper ends and pivotally connected to the lower rear end portion of the basket at their lower ends, and a latch-acting link at the front end of said basket hung from said overhead support and detachably engageable with the front end of the basket, to hold the basket in the normal receiving position noted. 5

CARL E. CARLSON. 10
